UNITED STATES PATENT OFFICE

VITO G. PINAGLIA, OF WEST HAVEN, CONNECTICUT

DESIGN FOR A SUPPORTED AND BRACED CRYPT LAMP

Application filed September 16, 1929. Serial No. 32,770. Term of patent 7 years.

To all whom it may concern:

Be it known that I, VITO G. PINAGLIA, a subject of the King of Italy, residing at West Haven, in the county of New Haven and State of Connecticut, have invented a new, original, and ornamental design for a Supported and Braced Crypt Lamp, of which the following is a specification, reference being had to the accompanying drawing, forming part thereof.

The figure is a side elevational view of a supported and braced crypt lamp, showing my new design.

I claim:—

The ornamental design for a supported and braced crypt lamp, as shown.

VITO G. PINAGLIA.
